UNITED STATES PATENT OFFICE

ROBERT D. DUNCAN, JR., OF EAST ORANGE, NEW JERSEY, ASSIGNEE, BY MESNE ASSIGNMENTS, TO FEDERAL TELEGRAPH COMPANY, A CORPORATION OF CALIFORNIA

HIGH-FREQUENCY SYSTEM

Application filed February 15, 1926. Serial No. 88,279.

My invention relates broadly to the generation of polyphase high frequency currents, and more particularly to electron tube apparatus and circuits for the production of 5 polyphase high frequency currents for signal transmission systems.

One of the objects of my invention is to provide a type of multi-element electron tube and a system of circuits by means of 10 which direct current may be converted by the electron tube into polyphase and in particular three phase high frequency current.

Another object of my invention is to provide an electron tube structure and circuits 15 by which means direct current may be converted into polyphase and in particular three phase alternating current in which all even harmonics and all triple frequency harmonics of the fundamental frequency are suppressed.

Still another object of my invention is to provide a transmission and modulation system employing a polyphase electron tube structure and system of circuits.

A further object of my invention is to provide a high frequency current generation system in which single phase high frequency current may be converted into polyphase high frequency current for polyphase electric power transmission.

Still another object of my invention is to provide a practical construction of a polyphase high frequency current generator which may be operated from sources of direct current or single phase high frequency current normally available for the supply of polyphase high frequency electrical energy for space radio or wired radio broadcast transmission.

A still further object of my invention is to provide an electron tube structure and circuit arrangement for the production of a revolving electrostatic field from a source of single phase high frequency current which 45 may be utilized by the interposition of related

electrodes and interconnecting circuits for deriving polyphase high frequency currents therefrom.

My invention will be more clearly understood from the specification hereinafter following by reference to the accompanying drawings, in which:

Figure 1 illustrates at *a*, *b*, *c* and *d* an assembled electron tube generator employed in the system of my invention and the parts of such generator; Fig. 2 is a side elevation of one of the arrangements of electron tube structure; Fig. 3 illustrates a circuit arrangement for the generation of three phase high frequency energy from a source of single phase high frequency energy employing an electron tube construction in accordance with my invention; Fig. 4 illustrates diagrammatically the construction of an electron tube and circuit arrangement which I provide for the generation of three phase high frequency currents with means in the circuits for balancing out the even harmonics and the triple frequency harmonics; Fig. 5 shows an application of the principle of my invention to the generation of six phase high frequency current; Fig. 6 is a diagrammatic view showing the relation of current flow in the several circuits of the electron tube generator circuit of Fig. 3; Fig. 7 shows a modified circuit arrangement for securing a displacement in phase of voltages derived from a single phase source which are impressed upon the three phase electron tube generating circuit; Fig. 8 illustrates a modified arrangement of electron tube structure and source of three phase high frequency energy by which polyphase high frequency electrical energy may be produced; and Fig. 9 illustrates an electron tube structure and circuit arrangement by which a single phase source of high frequency current is utilized to produce a revolving electric field within the electron tube structure by means of voltages displaced in phase by 45 degrees.

With the introduction of polyphase high frequency current transmission and reception systems the necessity for a generator of polyphase high frequency electrical energy has become essential. Applications of the 5 polyphase generation system of my invention described herein will be more clearly understood by reference to the following co-pending applications for Letters Patent: Serial No. 35,212, Robert D. Duncan, Jr., three 10 phase wired radio receiving circuits, filed June 5, 1925 now Patent 1,592,085, dated July 13, 1926; Serial No. 45,131, Robert D. Duncan, Jr., three phase high frequency system, filed July 21, 1925; Serial No. 45,132, 15 Robert D. Duncan, Jr., Samuel Isler, and Salvatore A. Barone, three phase high frequency system, filed July 21, 1925 now Patent 1,669,159, dated May 8, 1928; and Serial No. 45,948, Robert D. Duncan, Jr., duplex radio telephone system, filed July 24, 20 1925 now Patent 1,591,025, dated July 6, 1926 and Patent No. 1,560,505, issued November 3, 1925 to Robert D. Duncan, Jr., for 25 method of carrier frequency suppression.

Referring to the drawings in more detail the numeral 1 represents the filament of the electron tube system which in normal operation is heated to incandescence and which 30 may be composed of tungsten, thoriated tungsten or any other substance which is normally employed in the manufacture of filament wire. Filament 1 runs longitudinally with the glass container 2, shown here 35 in cylindrical form. Connections 3 illustrated in Figs. 2 and 3 are common with filament 1 and serve to convey the heating current thereto. Surrounding filament 1 at a distance therefrom and concentric therewith, is a latticed wire cylinder divided into 40 four segments 4, 5, 6, 7, having substantially the same areas. These four segments are disassociated from one another by spaces 8 with their longitudinal axes displaced by 45 90°. In the drawings the segments are shown to be of lattice construction, that is, a grid of wires running both longitudinally and transverse. Any similar type of construction may be employed such as perforated or slotted metal plates. Segments 4, 5, 50 6, 7, may not be solid construction. Surrounding both filament 1 and segments 4, 5, 6, 7, and at a distance therefrom are three plates 9, 10, 11, which are made of three 55 substantially equal segments of a hollow metallic cylinder concentric with filament 1 and segments 4, 5, 6, 7. Plates 9, 10, 11, are solid in construction, are separated from one another by spaces 12 and have their longitudinal axes displaced by angles of 120°. Filament 1, grid-segments 4, 5, 6, 7, and plates 9, 10, 11, are suitably housed and supported in a hermetically sealed glass vessel indicated at 2. Vessel 2 is evacuated 60 and the tube elements are treated so as to

drive off occluded gases by any of the usual methods. Connections from filament 1 are brought out at 3—3, from grid-segments 4, 5, 6, 7, at 13, 14, 15, 16, and from plates 9, 10, 11 at 17, 18, 19.

The electron tube structure thus consists of an evacuated glass vessel 2 supporting and containing a filament 1, surrounding which and concentric with which are, first, 70 four sets of grid-segments 4, 5, 6, 7, displaced from one another by angles of 90°, and second, by three sets of plates 9, 10, 11, displaced from one another by angles of 120°. Leads for connecting with the two ends of 75 the filament and to each of the grid-segments and to the plates are brought out through the walls of the glass and the joints suitably sealed.

By the tube construction and arrangement of plates 9, 10, 11, and the disposal of 80 the electrodes within the tube, polyphase alternating current may be generated. The arrangement shown in Fig. 5 is for generation of six phase alternating current. It consists of the filament 1 and grid-segment 90 4, 5, 6, 7 structure of Figs. 1, 2, 3. Instead of three plates there are, however, six plates 20, 21, 22, 23, 24, 25 disposed about grids 4, 5, 6, 7, the same as described for Figs. 1, 2, 3, plates 20, 21, 22, 23, 24, 25, 95 being displaced from one another, however, by angles of 60°.

The operation of the tube and associated 100 circuits for generating three phase high frequency current is best explained in reference to Fig. 3. In this figure the tube elements are numbered as indicated in Figs. 1 and 2. In addition numeral 26 represents a battery for rendering filament 1 incandescent to the proper degree. One terminal of battery 26 is grounded at 27. The negative terminal is here indicated. 28 represents a source of single phase high frequency current, which supplies energy to circuit 30 through the means of transformer 29. Circuit 30 consists of secondary coil 32 of transformer 29, variable inductance 33, variable capacity 34, and primary coil 36 of transformer 35. Inductively 105 coupled to circuit 30 is a second circuit 31 consisting of secondary 37 of transformer 35, variable inductance 38 and variable capacity 39. Connected to the two terminals of capacity 34 through connections 13, 15, 110 are the grids 4, 6, of the tube. Connected to the two terminals of capacity 39 through connections 14, 16, are the two remaining grids 5, 7, of the electron tube. Bridged across grids 4, 6, 5 and 7, are respectively, high 115 series connected resistances 40—41 and 42—43, the midpoints of which are connected to the negative terminals of batteries 44 and 45, the positive terminals of which are grounded at 27. Plate 9 of the tube is connected through connection 17 through ca- 120 125 130

pacity 46 to one terminal of inductance 47, the other terminal of which is grounded at 27 through connection 48. In a similar manner, plates 10 and 11 are connected through 5 capacities 51 and 51^a to one terminal each of inductances 50 and 52 through connections 18 and 19. The remaining terminals of inductances 50 and 52 are connected with the grounded terminal of inductance 47 10 through the common connection 48. It will be noted that inductances 47, 50 and 52 are connected in the well known Y or star, three phase manner. Plates 9, 10, and 11 receive their requisite high positive voltage 15 from source 49, here shown as a battery, the negative terminal of which is grounded at 27. The positive terminal is connected through the choke coil 200, and there-through to the high frequency choke coils 201, 202 and 203, respectively, to plates 9, 10, 11. The plate 54 of electron tube 55 also receives its high positive voltage from battery 49 through choke 200. The filament 56 of the tube 55 is grounded at 27. Grid 25 57 is connected through the secondary 58 of speech input transformer 59, and through biasing battery 60 to the grounded terminal of filament 56. The primary 61 of transformer 59 is connected in series with microphone 62 and battery 63. It will be observed that tube 55 with its associated speech input apparatus serves merely to effect modulation by voice or otherwise, of the high frequency output of tube 2 by one of the 30 well known methods of modulation. Inductively coupled to inductances 47, 50, 52, are secondary inductance coils 64, 65, 66, each of which preferably has in series variable inductances 67, 68, 69. Inductances 40 64, 65, 66, 67, 68, 69, are interconnected in Δ in the three phase manner. At the apexes of the Δ connections 70, 71, 72, are made through variable capacities 73, 74, 75, to the ultimate load for tube 2, here indicated as 45 a three phase transmission line 76.

In Fig. 3 as well as in the other figures, circuit connections to ground 27 bring such points to the same potential and, therefore, serve as a point of common connection.

50 Single phase high frequency source 28, by virtue of coupling at transformers 29 and 35 will establish currents in circuits 30 and 31. With suitable adjustment of these two circuits, with the proper coupling at transformer 35, and further, with circuit 31 adjusted to be substantially in resonance with the frequency of source 28, the currents in circuits 30 and 31 may be made to differ in time phase by 90°. Since the voltage de-

60 veloped across a capacity is given by $\frac{1}{C} \int idt$, where C is the capacitance of the condenser, *i* the traversing current and *dt* the differential time, the voltages developed across capacities 34 and 39 must also be 90° out of

phase. By means of connections 13-15 and 14-16 these quadrature voltages are impressed on the grids 4-6 and 5-7 within the evacuated vessel 2.

Under these conditions there is then produced between and around grids 4, 5, 6, 7, which practically constitute the armatures of two condensers, in accordance with fundamental electrical theory, a rotating electric field, which revolves in synchronism with the frequency of source 28, the effective axis of revolution being substantially the filament 1 of the tube. If the circuits 30, 31, are properly adjusted the revolving field will be circular, that is, the field will have the same value for all points of its angular displacement, which is a preferred condition. The electric field rotating about filament 1 will, for example, when it is directed from grid 4 to grid 6, that is, when grid 4 is positively charged and grid 6 is negatively charged, cause an increase in the flow of electrons from filament 1 to plate 9, or an increase in current from plate 9 to filament 1. 180 time degrees later the field is acting in the opposite direction resulting in a decrease in plate current from the direct current condition. The resulting current flow in circuit of plate 9 is represented diagrammatically in Fig. 6 (a). Assuming that the field revolves in a clockwise direction, 120 time degrees after it is such as to cause an increase in plate current of plate 9, it will cause a similar increase in the current to plate 10, as shown in Fig. 6 (b). Likewise 100 120 time degrees after this condition, it will cause a similar increase in current to plate 11 as shown in Fig. 6 (c). When the action of the field is to cause a decrease in the flow of electrons to plates 10 and 11, a decrease in the current flowing therefrom will result. Therefore, under the action of the revolving electric field of grids 4-6, 5-7, and in accordance with the well known laws governing the flow of electrons in an evacuated space between a hot cathode and cold positively charged anodes, in the presence of varying interposed charges in the field between the hot cathode and the cold anodes, the direct current as drawn from source 49 115 will be converted into alternating current in the branches 46-47, 49-50, 51-52, of the same frequency as the driving source, and because of the angular displacements of plates 9, 10, 11, within the tube, the three alternating components of the plate currents flowing in circuits composed of elements 46-47, 49-50 and 51-52, will differ in time phase by 120°. A three phase electron tube generator of high frequency currents is thus obtained. In Fig. 3 due to the coupling between coils 47-64, 50-65 and 52-66 and to the Δ connection of coils 64-67, 65-68 and 66-69, three phase cur- 125 130

rents are established in the transmission lines 76.

Another way of viewing the action within the tube is that the rotating electric field 5 produces a rotating stream or cloud of electrons to revolve about the filament 1 as an axis. When the electronic stream is made to impinge upon any one of the three plates 9, 10, 11, a current will pass across the evacuated space to filament 1. The angular displacement by 120° of the three plates 9, 10, 11, around filament 1, by virtue of the action of the rotating electron stream provides a means for generating alternating currents in 15 the circuits connected with plates 9, 10, 11, which will differ in time phase by 120°.

The function of high resistances 40—41, 42—43, which may or may not be required, is to afford a leakage path to the grounded 20 filament 1 for the excess electrons which may collect on grids 4—6 and 5—7. Batteries 44 and 45 which may or not be required, serve to provide the proper negative biasing voltage for the grids 4—6, 5—7.

Modulation of the output of tube 2 is effected by means of tube 55 and associated apparatus. This tube, in the well known manner, functions as an audio or speech frequency amplifier, the audio frequency voltage developed over the chock coil 200 being applied in effect in series with the voltage of source 49 to plates 9, 10, 11. Condensers 46, 49 and 51 in accordance with usual procedure have a sufficiently high reactance at 35 audio frequencies to block the flow of audio frequency current from the paths containing them. High frequency choke coils 201, 202 and 203, together with capacities 46, 49, 51, in the usual combination form a filter for separating out the high frequency alternating and continuous components of the current to plates 9, 10, 11.

The circuits and tube shown in Fig. 5 are for the production of six phase high frequency current in the six phase load indicated in its entirety by 77. The plates 20, 21, 22, 23, 24, 25, are connected in the usual double Y or double start six phase manner through circuits 78, 79, 80, 81, 82, 83, and 50 common connection 84 to ground 27. Only the alternating components of the plate circuits are shown in Fig. 5. The plates obtain their requisite high positive voltage from the same source through high frequency choke coils as shown in Fig. 3.

The arrangement of circuits 30, 31 of Fig. 3, for obtaining two alternating voltages differing in time phase by substantially 90° with which to produce a revolving electric field is one which has been found to yield both flexibility and stability of operation. There are other methods of accomplishing this end, however, which are effective with the tube structure shown in Figs. 1, 2, 3, 4 65 and 5, and with the tube structure of Figs.

8 and 9. It is not the intention to limit the scope of this invention to any particular circuit or system of circuits for dephasing voltages or currents for producing the revolving electric field, as it will be understood 70 that any method which accomplishes this may be employed in conjunction with a polyphase tube of suitable internal structure.

Since an electron tube is inherently a 75 voltage operated device, the circuit arrangement of Fig. 7 may be employed. In Fig. 7, 28 (as in Fig. 3) represents a source of single phase high frequency current operating into circuit 85, consisting of variable inductance 86, variable resistance 87, and variable capacities 88 and 89 connected in series. If R represents the resistance of that portion of resistance 87 included between variable tap 90 and common connection 91, and C and ω respectively, the capacitance of capacity 88 and ($2\pi \times$ frequency) the voltages developed across these will be equal if $R = \frac{1}{\omega C}$ and in accordance with 90 fundamental electrical laws will be substantially 90° out of phase. Through connections 13—15, and 14—16 extending to grids 4—6, and 5—7, as shown in Fig. 3, a revolving electric field is produced within the poly 95 phase tube.

I have described particular methods for the production of revolving electric fields from two alternating voltages out of phase by 90°. It is possible to obtain revolving 100 electric fields under other conditions of phase displacement. The essential feature is that the phase difference in electrical degrees between the producing voltages be substantially the same as the angular displacement between the grids which produce the revolving field. For example, with the tube structures of Figs. 1 to 5 inclusive the pairs of grids 4—6, 5—7, are displaced by 105 90°, which is also the phase angle between 110 the producing voltages developed over capacities 34, 39.

In the tube structure of Fig. 8 the grids 92, 93, 94, are displaced by angles of 120°. The remaining filament and plate elements 115 for the tube are the same as the tube of Figs. 1 to 5 inclusive. The tube arrangement and circuit of Fig. 8 is intended for three phase high frequency current generation, though the six phase plate structure 120 of Fig. 5 may be used for six phase generation. To produce a revolving electric field between grids 92, 93, 94, the voltages impressed between the same must differ in time phase by 120°. Any suitable arrangement of circuits for obtaining three phase voltages may be used. For example, in Fig. 8, 101 represents a suitable type of three phase high frequency current generator, of the kind shown in my Letters Patent 130

1,578,881, dated March 30, 1926. Generator 101 operates into the three Δ connected primary inductances 95, 96, 97. Inductively coupled to the latter are three Y connected inductances 98, 99, 100, the common terminal of which is grounded at 27, through biasing battery 102 poled so that the positive terminal is grounded. The free terminals of inductances 92, 93, 94, produce around and between the same a revolving electric field or stream of electrons. The plates 9, 10, 11, through connections 17, 18, 19, may be connected in the same manner shown in Fig. 3.

The revolving field, similar to that of Figs. 1 to 5, rotates in synchronism with the frequency of the voltage of the source 101. If E represents the maximum intensity of the field produced by the 90° tube structures of Figs. 1 to 5, the maximum intensity of the field of the tube structure of Fig. 8 will be $1.5E$, as may be determined from a mathematical consideration of the amplitude and phase of the voltages involved.

The tube structure and circuit arrangement shown in Fig. 9 discloses a means for generating three phase current from the effects of a revolving electric field, in turn produced by voltages displaced in phase by 45° . In Fig. 9, 28 is a source of single phase high frequency current which operates into circuit 103 made up of variable inductance 104, variable capacity 117 and the primary inductances 109, 110, 111, 112, of transformers 105, 106, 107, 108. Secondary 113 and 114 of transformers 105 and 106 are, respectively, connected in series with capacity 118 and resistance 119, and capacity 120 and resistance 121. Secondary 115 is connected in series with resistance 122; secondary 116 is connected in series with inductance 123 and resistance 124. The capacities, resistances and inductances are preferably variable. In the tube 2 there are contained as before, filament 1, and plates 9, 10, 11, with output connections 17, 18, 19. The grid structure of the tube of Fig. 9 consists of four pairs of grids 125—129, 126—130, 127—131, 128—132, the adjacent grids being displaced by angles of 45° from each other. Connections 133, 137, extending from 125—129 connect with the opposite terminals of resistances 119. In a similar manner, leads 134—138, 135—139, 136—140 connect respectively, with the two terminals of resistances 121, 122 and 124. High resistances 141, 142, 143—144, 145—146, 147—148, are connected in series respectively, between the grids 125—129, 126—130, 127—131, 128—132. The midpoints of these resistances are connected through the common connection 150 to the negative terminal of battery 149, the positive terminal of which is grounded at 27. The output connections 17, 18, 19, may be associ-

ated with circuits as shown in Fig. 3. The filament 1 of tube of Fig. 9 is grounded at 27.

The driving voltages induced in each of secondaries 113, 114, 115, 116, lag the magnetic flux established by the current in series connected primaries 109, 110, 111, 112, by substantially 90° . With the proper ratio of reactance of capacity 118 to resistance 119, the current in the circuit 113—118—119 will lead the driving voltage of that circuit by substantially 90° . The voltage developed over resistance 119 will be in phase with the current and will also lead the driving voltage by 90° . With suitable adjustment of the reactance of capacity 120 and resistance 121, the current in circuit 114—120—121 will lead the driving voltage in this circuit by 45° . The voltage developed over resistance 121 will, therefore, also lead the driving voltage by 45° or lag the voltage developed over resistance 119 by substantially 45° . The current in circuit 115—122 is virtually in phase with the driving voltage induced in secondary 115. The voltage developed over resistance 122 therefore lags the voltages developed over resistances 119 and 121, respectively, by 90° and 45° . With suitable adjustment of the reactance of inductance 123 and resistance 124, the current in circuit 116—123—124 will lag the driving voltage induced in 116 by substantially 45° . The voltage developed over resistance 124 since it is in phase with the current will therefore lag the voltages developed over resistances 119, 121, 122, and 124, respectively, by 135° , 90° and 45° .

By means of the circuit connection and the tube structure of Fig. 9 a revolving electric field is produced within and around grids 125, 126, 127, 128, 129, 130, 131, 132. It may be shown that the maximum value of the revolving electric field is twice that obtained with grids displaced by 90° . With the output connections 17, 18, 19, from the three plates 9, 10, 11, interconnected with a three phase circuit and a source of direct current supply, such as is shown in Fig. 3, three alternating currents will be established which differ in time phase by substantially 120° , that is to say, a three phase electron tube generator is obtained.

The tube structure and circuits of Fig. 9 provide a very efficient means of three phase current generation. The principle illustrated in Fig. 9 may be further extended and a revolving field obtained by voltage displaced by 30° , 22.5° , 15° , 12° , 10° , or theoretically by any angle divisible into 360° , the only essential requirement is that the angular displacement between the grids of the tube be the same as the phase angle between the voltages which go to produce the revolving field. My invention is therefore susceptible to a number of modifications.

The tube structure shown in Fig. 4 consists of a filament 1, grids 4¹—6¹, 5¹—7¹, similar to grids 4—6, 5—7 of Figs. 1, 2, 3, but here shown as sections of a plane instead of a cylinder, and two sets each consisting of three plates, 9'', 10'', 11'' and 9''', 10''', 11''', also sections of planes instead of a cylinder. The grids are disposed around the filament in a 90° relationship; the 10 plates are displaced from each other by 120°. The filament 1 as before, is heated to the proper degree of incandescence by means of battery 26, the negative terminal of which is grounded at 27. Grids 4¹, 5¹, 6¹, 7¹, through leads 13¹—15¹ and 14¹—16¹ are assumed to be connected with condensers similar to 34, 39 of Fig. 3 to obtain two voltages out of phase by 90° with which to produce a revolving electric field around grids 4¹—6¹, 5¹—7¹. Plate 9'' through lead 17'' is connected through capacity 151, and inductance 152 to the ground 27 through common connection 153. Plate 9''' through lead 17''' is likewise connected through capacity 154 and 25 inductance 155 to ground 27 through common connection 153. In a similar manner, plates 10'' and 10''' through leads 18'' and 18''' are connected respectively, through capacities 156, 158 and inductances 157 and 30 159 to ground 27 through common connection 153. The same method of connection holds for plates 11'', 11''', through leads 19'' and 19''' respectively, through capacities 160, 162, and inductances 161, 163, to 35 ground 27 through common connection 153. Plates 9'', 9''', 10'', 10''', 11'', 11''' receive their high positive voltage from source 164, here represented as a D. C. generator of which the negative terminal is grounded at 40 27, through high frequency choke coils 165 and leads 166. It will be noted that the inductances 155, 157, 161, and 152, 159, 163, considered in order of three named, are Y connected with a common terminal 45 grounded, in the three phase manner, and function as the output inductances of the circuits containing plates 9''', 10''', 11''' and 9'', 10'', 11''. Inductively coupled with inductances 155—152, 157—159, 161—163, are 50 respectively, inductances 167, 168, 169, which are also connected in Y through common connection 170. These latter inductances operate into the final load, here represented as a three phase transmission 55 line 177, through variable inductances 171, 172, 173, and variable capacities 174, 175, 176.

By the principles outlined herein, the revolving electric field produced by the grids 4¹, 5¹, 6¹, 7¹, will convert the direct current drawn from source 164 into three phase alternating current effective in the output plate circuits of the tube. The frequency of the three phase current is the same as that of 60 the single phase source which produces the

voltages utilized for obtaining the revolving electric field of grids 4¹—6¹, 5¹—7¹. Now the fundamental law of the three electrode electron tube (in this case the three electrodes comprising the filament, one grid and one plate), is well known to approximate the square relationship, that is, the plate current varies substantially as the square of the voltage applied between the grid and filament, for a given applied plate 70 voltage. Under this condition it may be proved and is well known that if the grid voltage is alternating, that is, a sinusoidal function, the output plate current in addition to the fundamental frequency component will contain all the even harmonics 80 thereof. The balanced plate circuit connection of Fig. 4 is fundamentally similar to the "push-pull" connection well known in the radio art, by which means the even harmonics are in opposition or balance out in their effect upon the final output circuit. In Fig. 4 this balancing effect is obtained by virtue of the connections between the paired plates 9''—9''', 10''—10''', 11''—11''', 85 and the usual differential placing of inductances 155—152, 157—159, 161—163, which are respectively, coupled to inductances 167, 168, 169, so that no even harmonic frequency currents will be induced in the latter. Furthermore, it is known in the electric power art that with the secondaries or output windings of three phase transformers connected in Y the odd harmonics of three times the fundamental frequency and multiples of 100 three, that is, 9, 15, 21, etc., are balanced out of and do not appear in the load. Odd harmonics may be and are generally present in the output circuit of an electron tube amplifier. Due to the Y connection of inductances 167, 168, 169 of Fig. 4, the triple frequency harmonics are balanced out of the load or lines 177.

The tube structure and circuit arrangement disclosed in Fig. 4 constitute a new 110 means for generating three phase high frequency current which is free from all even harmonics and from the triple frequency harmonics and all multiples thereof. The remaining harmonics may, therefore, be of the order 5th, 7th, 11th, 13th, etc., usually of rapidly diminishing amplitudes.

The elimination or partial elimination of harmonics is very essential in multiplex transmission, either for space or wired radio, 120 as otherwise with the displacement of fundamental frequencies to avoid interchannel interference it is virtually impossible to simultaneously avoid beating between some of the various harmonic frequencies.

As has heretofore been pointed out, the polyphase high frequency generator of my invention has numerous applications. The apparatus may be compactly arranged in a unit which is readily installed in a power 125 130

5 plant for super-imposing polyphase high frequency energy on polyphase transmission lines emanating from the power plant in a wired radio broadcasting system. Likewise, the apparatus may be compactly installed in a space radio broadcasting station in systems of carrier wave suppression in which polyphase signaling energy is employed as described in one of the aforementioned co-
10 pending applications for Letters Patent.

10 While I have described my invention in certain preferred embodiments, I desire that it be understood that modifications may be made and that no limitations upon the invention are intended other than those imposed by the scope of the appended claims.

15 What I claim and desire to secure by Letters Patent of the United States is as follows:

20 1. In a system for the generation of polyphase high frequency currents, the combination of a source of alternating current, and means for obtaining voltages differing in time phase from said source comprising an electron tube system, means for producing a revolving electric field in said electron tube system, circuits terminating in said revolving electric field, each of said circuits including a series connected inductance and capacity, means for balancing each circuit and a polyphase high frequency system connected with each of said circuits.

25 2. In a system for the generation of polyphase high frequency electrical energy, the combination of a source of alternating current, and means for deriving voltages displaced in phase from said source comprising an electron tube system, having means for producing a revolving electric field therein, a plurality of circuits terminating in said revolving electric field, a series connected inductance and capacity included in each of said circuits, and a polyphase high frequency system coupled to each of said inductances.

30 3. In a system for the generation of polyphase high frequency electrical energy, a source of alternating current, means for producing a plurality of voltages from said source differing in time phase, an electron tube system employing said plurality of voltages for producing a revolving electric field, a plurality of circuits terminating in said revolving electric field, a series connected inductance and capacity connected in said circuits, and a polyphase high frequency circuit coupled with the inductances in each of said circuits.

35 4. In a system for the generation of high frequency polyphase current, a source of alternating current, an electron tube system having a plurality of electrodes therein, means for producing a plurality of voltages differing in phase for exciting said elec-

trodes in differing time phase for producing a revolving electric field around said electrodes, comprising circuits terminating in said revolving electric field, an impedance shunting each circuit, a tuned circuit connected across selected ones of said impedances, and connections between said source and each of said tuned circuits.

5. In a system for the generation of high frequency polyphase electrical energy, the combination of a voltage source, circuits connected with said source for deriving a plurality of voltages therefrom, each differing in time phase, an electron tube system including a source of electrons, a plurality of independent grid electrodes surrounding said source of electrons, a plurality of independent plate electrodes surrounding said grid electrodes, a polyphase circuit interconnecting said plate electrodes, means for impressing said voltages differing in time phase upon said grid electrodes for producing a revolving electric field, impedances connected in shunt with selected sets of said grid electrodes, and independently adjustable circuits connected to said impedances and to said source.

6. In a system for the generation of polyphase high frequency electrical energy, the combination of a voltage source, means for deriving a plurality of voltages differing in time phase from said source, an electron tube system having a source of electrons therein, a plurality of grid electrodes surrounding said source of electrons, circuits for impressing said voltages of differing time phase on said grid electrodes for producing a revolving electric field within said electron tube system, a plurality of plate electrodes surrounding said grid electrodes, divided paths for current flow connected to each of said plate electrodes, and a polyphase circuit coupled to each divided path.

7. In a system for the generation of polyphase high frequency electrical energy, the combination of a voltage source, means for deriving voltages from said source differing in time phase with respect to each other, an electron tube system including a source of electrons, a plurality of sets of grid electrodes corresponding in number to twice the number of said voltages differing in time phase for producing a revolving electric field, a plurality of plate electrodes surrounding said grid electrodes and corresponding to the number of phases of high frequency current which it is desired to produce, circuits interconnecting said plate electrodes for the generation of polyphase high frequency electrical energy, each of said circuits including a pair of differentially coupled inductances for balancing out the even harmonic frequencies.

8. In a system for the generation of polyphase high frequency electrical energy, the

combination of a voltage source, means for deriving voltages therefrom differing in time phase, an electron tube system including a source of electrons, a plurality of sets of grid electrodes surrounding said source of electrons and corresponding in number to the number of differing time phase voltages impressed thereon, a plurality of plate electrodes surrounding said grid electrodes and corresponding in number to the number of phases of the polyphase energy generated by said electron tube system, circuits interconnecting said plate electrodes, said circuits each including a pair of differentially coupled inductances whereby polyphase high frequency electrical energy may be generated therein and even harmonic frequencies balanced out.

9. In a system for the generation of polyphase electrical energy, the combination of a voltage source, means for deriving voltages therefrom differing in time phase, an electron tube system, a source of electrons therein, a plurality of grid electrodes surrounding said source of electrons, a plurality of plate electrodes surrounding said grid electrodes, circuits interconnecting each of said plate electrodes, a pair of differentially coupled inductances included in each of said circuits, and means whereby a revolving electronic stream is produced around said source of electrons for generating polyphase electrical energy at a fundamental frequency while balancing out selected harmonic frequencies.

10. In a system for the generation of three phase high frequency currents, the combination of a source of single phase high frequency current, circuits connected with said source for deriving voltages differing in time phase, an electron tube system having a source of electrons, a plurality of sets of grid electrodes surrounding said source of electrons, connections for impressing said voltages across said electrodes for producing a revolving electronic field, a plurality of plate electrodes corresponding in number to the number of phases of current generated by said electron tube system, and independent circuits connected with each of said plate electrodes for the generation of three phase electrical energy said circuits each including a pair of differentially coupled inductance elements for balancing out selected harmonic frequencies.

11. In a system for the generation of three phase high frequency currents, the combination of a source of high frequency electrical energy, means for deriving voltages differing in time phase from said source of energy, an electron tube system having a source of electrons, a set of grid electrodes surrounding said source of electrons for each of said voltages, a plurality of plate electrodes surrounding said grid electrodes and corre-

sponding in number to the number of phases generated by said electron tube system, circuits interconnecting said plate electrodes, and a three phase circuit coupled with all of said circuits whereby a revolving electronic field impinges on said plate electrodes for the generation of three phase electrical energy in said circuits and a pair of differentially coupled inductances included in said circuits for opposing the effects of even harmonic frequencies in said circuits.

12. In a system for the generation of polyphase high frequency currents, the combination of a source of electrical energy, means for obtaining voltages differing in time phase from said source, an electron tube system, means for producing a revolving electric field in said electron tube system, circuits terminating in said revolving electric field, a polyphase circuit connected with said aforementioned circuits, means for generating polyphase electrical energy in said circuits, and means connected with each of said circuits for the elimination of even harmonics from said polyphase circuit comprising pairs of inductively coupled circuits connected to oppose the generation of predetermined harmonic frequencies.

13. In a system for the generation of three phase high frequency currents, the combination of a source of high frequency current, means for obtaining voltages differing in time phase from said source, an electron tube system, means for producing a revolving electric field in said electron tube system, circuits terminating in said revolving electric field, a three phase electric power distribution system connected with said circuits, and a pair of balanced circuits connected with each of said circuits for eliminating the even harmonics and all triple frequency harmonics of the fundamental frequency of said high frequency current source from said three phase system in the generation of three phase currents.

14. In a system for the generation of polyphase high frequency currents, the combination of a source of high frequency electrical energy, means for obtaining voltages differing in time phase from said source, an electron tube system, means for producing a revolving electric field in said electron tube system, balanced circuits each including inductance and capacity elements, said circuits terminating in said revolving electric field, a polyphase system coupled with the inductance elements of said balanced circuits, said balanced circuits providing means for eliminating even harmonics in said polyphase system.

15. In a system for the generation of high frequency three phase electrical energy, the combination of a source of high frequency current, circuits connected with said source for deriving a plurality of voltages there-

from, each differing in time phase, an electron tube system including a source of electrons, a plurality of sets of grid electrodes corresponding in number to twice the number of voltages of differing time phase, a pair of independent sets of plate electrodes surrounding said grid electrodes, with the number of plate electrodes in each set corresponding to the number of phase current generated in the three phase system, a three phase electrical load circuit, and a balanced electrical circuit connected between each phase of said electrical circuit and a plate electrode in each of said sets of plate electrodes for impressing three phase electrical current on said three phase load circuit free of even and triple frequency harmonics.

16. In a system for the generation of high frequency polyphase electrical energy, the combination of a high frequency voltage source, circuits connected with said source for deriving a plurality of voltages therefrom, each differing in time phase, an electron tube system including a source of electrons, a plurality of pairs of grid electrodes surrounding said source of electrons, branch circuits coupled to said source, potentiometers connected with each of said branch circuits, connections from said potentiometers for impressing voltage across each pair of grid electrodes for producing a revolving electronic field, a plurality of sets of plate electrodes surrounding said grid electrodes, a polyphase electrical load circuit, connections between each phase of said electrical circuit, and an electrode in each of said sets of plate electrodes for the production of polyphase current free of even harmonics and triple frequency harmonics.

17. In a system for the generation of polyphase high frequency energy, the combination of a source of voltage, an electron tube system comprising an evacuated vessel, a source of electrons therein, a plurality of pairs of grid electrodes mounted diametrically opposite each other on opposite sides of said source of electrons, potentiometers connected across said voltage source, connections between selected points on said potentiometers to said grid electrodes for impressing a voltage across one pair of said grid electrodes differing in time phase from the voltage impressed across another pair of said grid electrodes for producing a revolving electronic field about said electrodes, a plurality of plate electrodes surrounding said grid electrodes and corresponding in number to the number of phases of polyphase current generated by said electron tube system, a polyphase circuit, and connections between each phase of said polyphase circuit, and each of said plate electrodes for the generation of polyphase energy in said polyphase circuit.

18. In a system for the generation of poly-

phase electric currents, the combination of a source of voltage, an electron tube system comprising an evacuated vessel, a source of electrons therein, a plurality of pairs of grid electrodes positioned on diametrically opposite sides of said source of electrons, a plurality of branch circuits connected with said voltage source, connections between each of said branch circuits, and a potentiometer, connections between selected points on said potentiometer and a pair of said grid electrodes for impressing voltage across the respective pairs of grid electrodes differing in time phase relation for the production of a revolving electronic field, a plurality of plate electrodes, a polyphase circuit, and connections between said plate electrodes and each phase of said polyphase circuit for the generation of polyphase current in said polyphase circuit.

19. In a system for the generation of polyphase alternating currents, the combination of a source of voltage, an electron tube system comprising an evacuated vessel, a source of electrons therein, a plurality of pairs of grid electrodes positioned on diametrically opposite sides of said source of electrons, a plurality of branch circuits connected with said voltage source, resistances connected in shunt with each of said branch circuits, connections between the opposite terminals of said resistance and a pair of said grid electrodes, a connection between said resistances and said source of electrons for normally biasing said grid electrodes at a certain voltage with respect to said source of electrons, each of said branch circuits being arranged to impress voltages across said grid electrodes differing in time phase relations for establishing a revolving electronic field within an evacuated vessel, a plurality of plate electrodes surrounding said grid electrodes, a polyphase electrical circuit, and connections between said plate electrodes and said polyphase circuit for the generation of polyphase currents therein.

20. In a system for the generation of polyphase high frequency electrical energy, the combination with a voltage source, an electron tube system including a source of electrons, a plurality of grid electrodes surrounding said source of electrons, said grid electrodes extending adjacent said source of electrons, means connected with said voltage sources for impressing voltages lagging each other across opposite pairs of said grid electrodes for establishing a revolving electronic field around said grid electrodes, independent groups of plate electrodes corresponding to the number of phases generated, and mounted adjacent said grid electrodes, with the plate electrodes of each group disposed diametrically opposite each other, and a resistance bridging each of said groups of said electrodes, a polyphase electrical

circuit, and means coupled with each of said phases of said electrical circuit and connected with a plate electrode in each of said groups of electrodes for impressing polyphase electrical energy on said polyphase circuit.

21. In a system for the generation of three phase high frequency current, a source of single phase alternating current, circuits electrically connected with said source providing means for developing two voltages substantially equal in amplitude and differing in time phase by substantially 90 degrees, an electron tube system comprising an evacuated vessel enclosing a filament, and sets of grids and plates, said plates being three in number and disposed around and at a distance from said filament, and angularly displaced around said filament by substantially 120 degrees, connections from each of said plates to output inductances interconnected in a three phase manner, additional connections to each of said three plates for providing continuous voltage thereto, and additional inductances coupled to said output inductances and interconnected in a three phase manner for the development of a fundamental frequency free from selected harmonic frequencies.

22. In a system for the generation of three phase high frequency current, a source of single phase high frequency current, circuits electrically associated with said source providing means for developing two voltages substantially equal in amplitude and differing in time phase by substantially 90 degrees, an electron tube comprising an evacuated vessel enclosing a filament and sets of grids and plates disposed on diametrically opposite sides of said filament, said plates consisting of two groups each in number of three, each of said groups of three plates being disposed around and at a distance from different portions of said filament, the individual plates of each of said groups of three being angularly displaced around said different portions of said filament by substantially 120 degrees, connections from each plate of one of said groups of three plates to output inductances interconnected in three phase Y, and connections from each plate of the second of said groups of three plates to additional output inductances interconnected in three phase Y, said first and additional output inductances being interconnected in a balanced manner for the production of polyphase currents of a fundamental frequency free from selected harmonic frequencies.

23. In a system for the generation of three phase high frequency electrical energy, the combination of a source of single phase alternating current, means for obtaining voltages differing in time phase from said source, an electron tube system comprising

an evacuated vessel and therein a source of electrons, a plurality of sets of grid electrodes positioned on diametrically opposite sides of said source of electrons, circuits for impressing said voltages differing in time phase between opposing pairs of said grid electrodes for producing a rotating electric field between and around said grid electrodes and around said source of electrons, a plurality of sets of plate electrodes positioned on diametrically opposite sides of said source, each set corresponding in number to the number of phases, impedance circuits disposed in shunt with each set of said grid electrodes, and output circuits connected to each of said plate electrodes for the development of polyphase currents, and means for suppressing all even and triple frequency harmonics of the fundamental frequency from said output circuits.

24. In a system for the generation of polyphase electrical energy, a source of alternating current, circuits connected with said source for obtaining a plurality of voltages differing in phase, an electron tube system comprising an evacuated vessel, and therein a source of electrons, a plurality of grid electrodes positioned around said source of electrons means for impressing said plurality of voltages differing in phase on said plurality of grid electrodes for producing a rotating electric field around said source of electrons, a plurality of sets of plate electrodes corresponding in number to the number of phases of the polyphase generation system and positioned around said grid electrodes to receive electrons from different portions of said source of electrons, impedance circuits connected across each set of said grid electrodes, and output circuits connected with each plate of said plurality of sets of plate electrodes for the development of polyphase currents therein.

25. In a system for generating polyphase alternating current, a source of single phase alternating current, an electron tube system consisting of an evacuated vessel and therein a hot cathode for the emission of electrons, a plurality of grid electrodes surrounding said hot cathode, a plurality of plate electrodes surrounding said grid electrodes, impedances connected across selected groups of said grid electrodes, and output circuits connected with said plate electrodes, the potential drop across said impedances developing a rotating electric field between and around said grid electrodes for influencing the flow of electrons from said hot cathode to said plurality of plate electrodes for generating polyphase alternating currents in said output circuits.

26. In a system for the generation of polyphase alternating current the combination of an electron tube comprising an evacuated vessel and therein a source of elec-

trons, and a plurality of groups of grid and plate electrodes disposed on diametrically opposite sides of said source of electrons, resistors shunting the oppositely positioned grid electrodes, said electrodes operating to maintain a rotating electric field within said electron tube and a polyphase circuit connected to said plate electrodes for the generation of polyphase currents therein under control of said rotating electric field.

27. In an electric circuit the combination of an electron tube comprising an evacuated vessel and therein a source of electrons, and a plurality of groups of grid and plate electrodes distributed concentrically about said source on diametrically opposite sides thereof, impedances shunting sets of said grid electrodes, said electrodes operating to maintain a rotating electric field within said electron tube for influencing the flow of electrons to said grid and plate electrodes and a polyphase circuit connected to said plate electrodes for the generation of polyphase currents therein under control of said rotating electric field.

28. In a system for generating three phase alternating current comprising in combination a source of single phase alternating current, an electron tube system consisting of an evacuated vessel and therein a hot cathode for supplying electrons, a plurality of grid electrodes positioned around said hot cathode, three plate electrodes positioned symmetrically around said grid electrodes, and output circuits associated with said plate electrodes, said grid electrodes being supplied with energy from said single phase source for maintaining a rotating electric field between and around said grid electrodes for influencing the flow of electrons from said hot cathode to said grid and plate electrodes for generating three phase alternating current in said output circuits.

29. In a system for the generation of polyphase alternating current the combination of an electron tube comprising an evacuated vessel, a source of electrons therein, and a plurality of electrodes disposed on diametrically opposite sides of said source, impedances connected in shunt with selected groups of said electrodes, circuits interconnecting selected ones of said electrodes for maintaining a rotating electron stream within said electron tube and a polyphase circuit connected with other selected groups of said electrodes.

30. In a system for generating three phase alternating current comprising a source of single phase alternating current, circuits connected therewith for deriving two voltages of substantially equal amplitudes and differing in phase by substantially 90 degrees, an electron tube system comprising an evacuated vessel and therein a hot cathode for supplying electrons, two pairs of

grid electrodes with the electrodes of each pair positioned on diametrically opposite sides of said hot cathode, connections for impressing said two voltages differing in phase by substantially 90 degrees respectively between each of said pair of grid electrodes, three plate electrodes displaced around said grid electrodes by 120 degrees, impedances connected in shunt across pairs of said grid electrodes, and a polyphase circuit connected with said plate electrodes.
